Önventor,

James Acton Miller, by
Harry P. Williams.
Attorney.

UNITED STATES PATENT OFFICE.

JAMES ACTON MILLER, OF HARTFORD, CONNECTICUT.

LAMP.

SPECIFICATION forming part of Letters Patent No. 430,870, dated June 24, 1890.

Application filed March 21, 1890. Serial No. 344,839. (No model.)

To all whom it may concern.

Be it known that I, JAMES ACTON MILLER, a citizen of the United States, residing at Hartford, in the county of Hartford and State 5 of Connecticut, have invented certain new and useful Improvements in Lamps, of which the following is a full, clear, and exact specification.

The invention relates to the class of oil-lamps which can be adjusted to extinguish the flame when desired; and the object of the invention is to provide a simple and positive contrivance which may be set so that after a certain quantity of oil is consumed the wick 15 is drawn down into the wick-tube too far for the flame to burn.

Referring to the accompanying drawings, Figure 1 is a side view of a lamp provided with my improvement with the wick raised, 20 part of the shell being broken away to show the interior. Fig. 2 is a side view of the lamp with the wick drawn down into the wick-tube as when the flame is extinguished. Fig. 3 is a plan view of the same with the parts 25 set as when the wick is raised. Fig. 4 is a detail view, on an enlarged scale, of a part of the float-rod and adjustable catch.

In the drawings, where my improvement is shown as applied to a central-draft lamp, the 30 letter *a* indicates the shell, *b* the wick-tube, and *c* the circular wick which surrounds the central draft-tube *d*, and is adjustable between the wick-tube and the draft-tube. A rod *e*, which passes into the shell, is attached 35 at one end to the wick, preferably by a band of metal *e'*, while the outer end is connected with the adjusting-rod *f*, that passes down through the shell and terminates in a handle *f'* below the oil-chamber. Upon this rod is 40 placed a sliding tube *g*, that is normally held downward by the pressure of a spring *h*. This tube is provided with a set-screw *g'*, whereby it may be secured to the rod, and with a lug or collar *g''*, that projects into the 45 path of oscillation of a lever *i*. The lever *i*, which has an oscillation at right angles to the movement of the rod *f* and tube *g*, is so pivoted to a stud rising from the shell that when the tube is lifted the lever may be moved so that 50 one end will engage the projecting collar *g''* and prevent the spring from drawing the tube downward. When in this position, the op-

posite end of the lever is held by a hook *j'*, that projects from a catch *j*, borne by a rod *k*, which passes into the oil-chamber and is connected with a float *l*. This catch *j*, which has the hook *j'*, preferably consists of a sliding collar, to which is pivoted a latch *j''*, provided with a tongue *j'''*, adapted to fit into a series of notches, indentations, or graduations which 55 are formed on the rod *k* to hold the catch at the desired height on the rod. A spring *m* normally presses the longer arm of the lever away from the hook *j'*, and a plate *n* is attached to form a guide and stop for this arm 60 of the lever when it moves. When the set-screw *g'* is loosened so that the rod *f* is free from the tube *g*, the wick may be adjusted in the common manner by means of the rod *f*, which is joined to the rod *e*, that is connected 65 to the wick in the oil-chamber.

In order to set the device so that the flame may be extinguished at the desired moment, the catch *j* is adjusted to the desired graduation on the rod *k* and the end of the oscillating lever *i* engaged by the hook *j'*, so that when a certain amount of oil is consumed and the float permitted to drop the lever is disengaged from the hook *j'*, and under the impulse of the spring *m* is thrown outward, 75 and this draws the opposite end of the lever from beneath the collar *g''* on the tube *g*, where it was placed, and allows the spring *h* to suddenly draw down the tube and the rod *f*, with which it is connected by the set-screw. 80 This movement of the rod draws the wick downward between the wick-tube and the draft-tube so far that the combustion of the oil can no longer take place and the flame will 85 go out. The catch *j* is adjusted upon the rod *k*, preferably by means of a collar bearing the pivoted latch that swings into and out of the notched graduations, so that the float may be adjusted with relation to the oil in the lamp without any light; but the collar may, if desired, be connected to the rod by a set-screw. 90

I claim as my invention—

1. In combination with the wick of a lamp, a rod attached to the wick and adjustably connected, with a sliding spring-actuated rod, and a lever held in engagement with the spring-actuated rod by a catch that is forced upward by the buoyant pressure of a float in the oil-chamber, substantially as specified. 100

2. In combination with the wick of a lamp, an adjusting-rod connected at one end to the wick and terminating at the other in a handle, a sliding tube adapted to be secured to the adjusting-rod, and a lever pivoted to the shell and adapted to oscillate to engage the tube with one end and with the other a catch attached to a rod connected with a float in the oil-chamber, substantially as specified.
- 5 10 3. In combination with the wick of a lamp, an adjusting-rod connected at one end to the wick and terminating at the other in a handle, a sliding tube adapted to be secured to the adjusting-rod, a spring to pull the tube downward, and a lever pivoted to the shell and adapted to oscillate to engage the tube with one end and with the other a catch attached to a rod connected with the float in the oil-chamber, substantially as specified.
- 15 20 4. In combination with the wick of a lamp, an adjusting-rod connected at one end to the wick and terminating at the other in a han-

dle, a sliding tube adapted to be secured to the adjusting-rod by means of a set-screw, and a lever pivoted to the shell and adapted to oscillate to engage the tube with one end and with the other a catch attached to a rod connected with a float in the oil-chamber, substantially as specified.

25 30 5. In combination with the wick of a lamp, an adjusting-rod connected at one end to the wick and terminating at the other in a handle, a sliding tube adapted to be secured to the adjusting-rod by means of a set-screw, a spring to pull the tube downward, and a lever pivoted to the shell and adapted to oscillate to engage the tube with one end, and with the other a catch attached to a rod connected with a float in the oil-chamber, substantially as specified.
